UNITED STATES PATENT OFFICE

152,923

DESIGN FOR A COMBINATION COMB AND BRUSH CLEANER

Nathan L. Solomon, Englewood, N. J.

Application October 31, 1947, Serial No. 142,238

Term of patent 14 years

(Cl. D9—2)

To all whom it may concern:

Be it known that I, Nathan L. Solomon, a citizen of the United States, residing at Englewood, in the county of Bergen and State of New Jersey, have invented a new, original, and ornamental Design for a Combination Comb and Brush Cleaner, of which the following is a specification, reference being had to the accompanying drawing, forming part thereof.

Fig. 1 is a face view of a combination comb and brush cleaner showing my new design.

Fig. 2 is a side view of the structure shown in Fig. 1; and

Fig. 3 is a plan view of the structure as shown in Fig. 2.

I claim:

The ornamental design for a combination comb and brush cleaner as shown.

NATHAN L. SOLOMON.
